US00D696212S

(12) **United States Design Patent**
Chen

(10) **Patent No.:** **US D696,212 S**
(45) **Date of Patent:** **** Dec. 24, 2013**

(54) **DISPLAY**

(75) Inventor: **Szu-Yin Chen**, New Taipei (TW)
(73) Assignee: **Top Victory Investments Ltd.**, Harbour (HK)

(**) Term: **14 Years**

(21) Appl. No.: **29/404,127**

(22) Filed: **Oct. 17, 2011**

(51) LOC (9) Cl. **14-03**

(52) U.S. Cl.

USPC **D14/126**

(58) **Field of Classification Search**

USPC ..... D14/125-134, 239, 371, 136, 374-377, D14/440, 450, 448, 336, 342, 159; 312/7.2; 348/836, 838, 180, 184, 325, 739; 341/12; 248/917-924, 465; 345/104, 345/133, 156, 168, 87, 173; 720/605, 669, 720/600, 655; 369/99, 197; D21/329, 515, D21/577, 622, 333, 433, 448, 452, 450, D21/331; D6/477, 479, 300-310; 273/148 B; 446/484, 175, 356; D10/15, D10/26
